DISPLAY RACK OR SIMILAR ARTICLE

Maurice Duchin, New York, N. Y.

Application March 12, 1954, Serial No. 29,482

Term of patent 3½ years

(Cl. D80—10)

To all whom it may concern:

Be it known that I, Maurice Duchin, a citizen of the United States of America and a resident of the city of New York, in the county of New York and State of New York, have invented a new, original, and ornamental Design for a Display Rack or Similar Article, of which the following is a specification, reference being had to the accompanying drawing, forming a part hereof, wherein the single figure is a perspective view of a display rack or similar article showing my new design.

I claim:

The ornamental design for a display rack or similar article, substantially as shown.
